C. F. WALTHER.
HEATING STOVE.

No. 19,541.

Patented Dec. 31, 1889

UNITED STATES PATENT OFFICE.

CHARLES F. WALTHER, OF BUFFALO, NEW YORK, ASSIGNOR TO SHERMAN S. JEWETT & CO., OF SAME PLACE.

DESIGN FOR A HEATING-STOVE.

SPECIFICATION forming part of Design No. 19,541, dated December 31, 1889.

Application filed October 28, 1889. Serial No. 328,466. Term of patent 14 years.

To all whom it may concern:

Be it known that I, CHARLES F. WALTHER, a citizen of the United States, residing at Buffalo, in the county of Erie and State of New York, have invented and produced a new and original Design for Stoves, of which the following is a specification.

This design is for a heating-stove having a square base and ash-pit section and a round body and top; and its leading features consist of the novel ornamentation of the stove as a whole, and also in the novel ornamentation of the segregable parts thereof, and in the shape or configuration of the legs, as will be hereinafter described and as is illustrated in the accompanying photographs.

Each skirting of the base A is ornamented centrally with a crescent-shaped design, between the horns of which is a leaf ornament 2. Upon the crescent are circular ornaments decreasing in size from the center toward the horns, and a leaf ornament 3 extends from each side of the crescent toward the corner of the base. The faces of the ash-pit section B are provided with braid-like designs 4, which have their ends terminating in leaf designs, and are near their ends made into double loops, forming 8-like figures, and centrally have a single loop between the 8-like figures. Between the different loops of the braid design are leaf ornaments, while the draft-openings occupy the spaces inclosed by the loops of the design on the front face of the ash-pit section, and on the other sides the spaces so inclosed are provided with leaf ornaments. The top C of the ash-pit section is ornamented at each corner with a volute and leaf design 5. The lugs D are expanded above the feet portions thereof, so as to have the appearance of being provided with caps 32, covering the corners of the base of the stove and lying over or upon the skirting thereof. These caps are made ornamental, and, in order to harmonize with the other designs of the stove, leaf and volute designs have been chosen for such ornamentation. Above the cap 32 the leg design is continued along the covers of the ash-pit section, so that the contour of the leg design from the foot section or portion thereof 33 to the top is

that of an ogee or similar curve. This latter feature gives a very graceful appearance to this portion of the stove, and, further, the upper portion of the leg being thrown outward makes an apparently natural rest or support 55 for the foot bar or rail E.

The body F of the stove has an ornamental front, which, for convenience of description, I will divide into four sections—the lower-door section 7, the middle section 8, the upper-door section 9, and the upper section 10. The lower-door section 7 has scroll ornamentations 11 on its face and leaf and volute ornamentations 12 near the hinge. The middle section 8 has a design of general triangular 65 shape, with its apex pointing downward, the design being made up of a central leaf ornament 13 and two lateral leaf ornaments 14, spreading outward and upward from the apex of the triangle. Below this triangular 70 design and to either side of the apex thereof are ornaments 15, similar in general effect to the ornament 12 of the lower-door section. The upper-door section 9 is ornamented with scroll-work 16, of the same general character as 75 that which appears upon the lower-door section, although differently arranged so as to radiate from the circular damper 17. Leaf and volute ornamentations 18 appear adjacent to the hinges. The ornamentation of 80 the upper section 10 is in general effect similar to that of the middle section—that is, it has a substantially triangular central design formed of a central leaf ornament 19 and the laterally and upward spreading leaf ornaments 20. The leaf ornaments 21 to the sides of the central design have their inner ends 22 carried upward and curved inward to complete the upper portion of the triangle.

The top G of the stove is of dome shape 90 surmounted by a ball. Below the band or rim 23, which serves as the base of the dome-shaped portion of the top and connecting it with the body of the stove, is a section 24, ornamented with a series of leaf designs. 95 Above the rim 23 is an ornamental section 25, consisting of a series of leaves, which are separated from each other by scroll-work drawn on heavy lines.

26 designates another plain band, which 100

separates the ornamental section 25 from another ornamental section 27. The latter has a series of volute ornaments 28, separated by ornamented sections 29. Above this section 27 rises the pedestal 30, which supports the ornamental ball 31. The lower zone of this ball is ornamented with half-stars and semi-circles. The middle zone has two vertical fluted portions separated by a plane belt or band, and the upper zone has leaf ornamentation. The ball 31 is surmounted by a smaller ball or knob 34.

Having thus described in detail my design for a stove, what I claim is—

- 15 1. In a design for a heating-stove, the design for the base, consisting, essentially, of the crescent and leaf ornaments, substantially as described and shown.
- 20 2. In a design for a heating-stove, the ash-pit section having its sides ornamented with the braid-like design formed into double loops near its ends, forming figures 8, and a single central loop, substantially as described and shown.
- 25 3. In a design for a heating-stove, the design for the top of the ash-pit section, consisting

of the volute and leaf ornaments, as described and shown.

4. In a design for a heating-stove, the surface ornamentation of the legs, as shown and 30 described.

5. In a design for a heating-stove, the legs having the shape or configuration shown and described.

6. In a design for a heating-stove, the body 35 having as essential ornamentations the two triangular-shaped ornamentations and the two sections of scroll-work ornamentations, substantially as described and shown.

7. In a design for a heating-stove, the top 40 having as essential ornamentations the leaf-ornamented section 25 and the volute-ornamented section 27, substantially as described and shown.

8. The design for a heating-stove, substantially as shown and described.

In testimony whereof I affix my signature in presence of two witnesses.

CHARLES F. WALther.
